Primary Examiner — Angela J Lee*Assistant Examiner* — Shawn T Gingrich(74) *Attorney, Agent, or Firm* — Tomlinson McKinstry, P.C.(57) **CLAIM**

The ornamental design for an electrical connection cover, as shown and described.

DESCRIPTION

FIG. 1 is a front view of an electrical connection cover, showing our design.

FIG. 2 is a bottom left front perspective view thereof.

FIG. 3 is a top left front perspective view thereof.

FIG. 4 is a left side view thereof. The left side and right side are mirror images.

FIG. 5 is a back view thereof.

FIG. 6 is a top view thereof.

FIG. 7 is a bottom view thereof.

FIG. 8 is a top left back perspective view thereof; and,

FIG. 9 is a bottom left back perspective view thereof.
